FILING CABINET

James A. Hedges, Chicago, Ill.

Application June 10, 1935, Serial No. 25,889

2 Claims. (Cl. 45—2)

My invention relates to the disposition of correspondence, records, documents, or the like, and has among its objects and advantages the provision of an improved filing cabinet.

5 The invention embodies certain improvements over my co-pending application Ser. No. 728,760.

In the accompanying drawing:

Fig. 1 is a perspective view of a cabinet unit, partly in section;

10 Fig. 2 is a sectional view along the line 2—2 of Fig. 1;

Fig. 3 is a view illustrating a number of units arranged in stacked relation;

15 Fig. 4 is a sectional view along the line 4—4 of Fig. 3; and

Fig. 5 is a perspective view of one of the inter-connecting clips.

20 In the embodiment selected to illustrate my invention, I make use of a drawer 10 and a cover

20 Fig. 2. The drawer 10 is slidably supported upon two runners 14 integrally connected with a cross

part 16. These runners are L-shaped in cross section, with the horizontal flanges supporting the load and the vertical flanges supporting the

25 tray against lateral shifting. I connect a metallic strap 18 across the ends of the runners 14 for

bracing purposes.

A pair of supporting loops 20 is connected with the runners 14 for supporting the cover 12. The

30 top of the cover fits snugly against the bights 22,

while the flanges 24 of the cover lie adjacent the vertical reaches 26 of the loops 20. These

loops are channel-shaped in cross section. Rivets

28 connect the cover 12 with the bights 22.

35 Referring to Figs. 1 and 2, the cover 12 comprises a fiber board shell 30 bent to define the

flanges 24, which flanges are reenforced by wood

strips 32. These strips may be glued or riveted

to the flanges 24 and lie in a plane common to

40 the walls 34 of the tray. I cut the ends 36 of

the strip 32 at an angle corresponding to the

angularity of the inclined edge 38 of the walls

34. These ends and edges are arranged in jux-

45 tapposed relation when the drawer 10 is closed.

45 In Fig. 2, the flanges 24 lie in the same plane

as the vertical flanges of the runners 14.

I provide means for stacking units according to

Fig. 1 in nested relation. To this end, the lower

end of each vertical reach 26 carries a pin 40.

50 This pin passes through aligned openings in its

respective vertical reach 26 and the vertical

flange of the runner 14, and has one end riveted

as at 42 and a flange 44 bearing against the

bight part of the reach 26. This pin extends be-

55 yond the flange 44 and provides a connecting ele-

ment for a clip 46 having an opening for the reception of the pin (see Fig. 4).

Each reach 26 is provided with a screw 48 near its upper end. These screws have threaded relation with the bight of the vertical reaches 26. 5 The clips 46 are slotted to receive the screws 48. The slotted feature provides adjustment so that the clips may be easily connected with the pins 40. Thus, the runners 14 of an upper unit rests upon the horizontal parts of the loops 20 associated with the unit underneath.

After the units have been stacked, the clips 46 are connected with the pins 40 and the screws 48 tightened. The clips 46 prevent lateral shifting of the stacked units as well as vertical separation, 10 and tie the units into a rigid assembly. When the units are used individually, the clips 46 are housed within the channel-shaped reaches 26. Diagonal braces 50 are riveted to the runners 15 14 and one of the loops 20 for bracing the 20 loops.

It will be noted that the loops 20 support the load of the superimposed units. In this way, the load of each tray is limited to the contents therein. My construction eliminates the necessity for 25 an enclosing shell for all the drawers. The individual units are kept apart from association with other units, and the grouping of units may be accomplished without changing or adjusting the individual units. 30

Since the load is transmitted to the loop structure, the drawer 10 together with the cover may comprise materials having relatively little compressive strength. The cover 12 supports no load. The units stack in regular formation, while the 35 construction of the units is such as to permit complete withdrawal of the drawers. The flanges 24 co-operate with the side walls 34 in such a manner as to provide a dust-tight relation.

Without further elaboration, the foregoing will 40 so fully explain my invention that others may, by applying current knowledge, readily adapt the same for use under various conditions of service.

I claim:

1. In a filing device, two tray supporting 45 frames arranged in stacked relation, each frame including vertical reaches, the vertical reaches of one frame being arranged in end to end alignment with the vertical reaches of the other frame, each vertical reach of the upper frame being provided with a laterally projecting pin near its lower end, each vertical reach of the lower frame being provided with a fastening screw, and a clip carried by each screw, each clip being slotted 50 longitudinally for loosely receiving its respective 55

fastening screw, the other end of each clip being provided with an opening for loosely receiving the pin carried by the associated vertical reach of the upper frame, said clips being firmly secured to said pins when said screws are tightened.

5. 2. In a filing device, two tray supporting frames arranged in stacked relation, each frame including a vertical reach U-shaped in cross section, the bight of the upper reach being provided

ed with a pin projecting laterally therefrom, a screw carried by the bight of the lower reach, and a clip mounted on said screw, said clip including a slot for loosely receiving the screw, said clip including an opening for loosely receiving said pin, the clip being firmly connected with the pin when said screw is turned down.

5
JAMES A. HEDGES.
